[57] CLAIM

The ornamental design for a two-handed dual-mode game controller, as shown and described.

DESCRIPTION

FIG. 1 is a top, front, left side perspective view of a two-handed dual-mode game controller showing our new design;

FIG. 2 is a right side elevational view, the left side being a mirror image thereof;

FIG. 3 is a front elevational view thereof;

FIG. 4 is a top plan view thereof; and,

FIG. 5 is a rear elevational view thereof.
